WIRE CONVEYER BELT

Ira H. Harter, Grays Lake, Ill.

Application April 18, 1932. Serial No. 606,002

17 Claims. (Cl. 198—193)

The invention relates in general to conveyer belts with more particular reference to a wire conveyer belt of specially formed sections which interlink with each other in a novel manner, giving to the belt a number of desired characteristics.

An object of the invention is to provide a wire conveyer which can be made of any width desired and which will consist of sections, each section being composed of two strands of wire having interlinking engagement with each other and with adjacent sections whereby a length of conveyer can be joined, forming an endless belt, which can subsequently be adjusted from time to time as to length by the omission or addition of individual sections.

A further object is to provide a conveyer belt formed of wire strands wherein alternate strands have similar characteristics with strands of dissimilar characteristics being connected together in pairs, each pair comprising a section of the conveyer, and which can be readily interlinked with other sections by reason of the novel formation of the strands.

Another object is the provision of a wire conveyer having a thickness equal approximately to twice the thickness of the wire from which it is fabricated and which will be constructed of transverse strands interlinked in a manner whereby the conveyer may be bent in one direction at approximately an angle of ninety degrees. In addition to maintaining the thickness of the present form of conveyer to not more than twice that of the wire from which it is formed one surface of the conveyer is also substantially flat, presenting a fairly even area for supporting objects thereon. This latter feature is especially desired in conveyer belts and in order to render the belts satisfactory for certain uses a substantially flat upper surface combined with extreme flexibility so as to pass over a right angled edge is a prerequisite.

The present type of wire conveyer fulfills the above conditions and others in an efficient manner, although of relatively simple construction, presenting, however, a strong and durable conveyer adaptable to many uses.

With these and various other objects in view, the invention may consist of certain novel features of construction and operation, as will be more fully described and particularly pointed out in the specification, drawing and claims appended hereto.

In the drawing, which illustrates an embodiment of the device and wherein like reference characters are used to designate like parts—

Figure 1 is a plan view of a portion of wire conveyer, the same being constructed in accordance with the present invention;

Figure 2 is a plan view of one of the sections of the wire conveyer showing more clearly the particular formation of the wire strands;

Figure 3 is a sectional view taken on line 3—3 of Figure 1;

Figure 4 is a fragmentary plan view showing the manner of interlinking two sections of the conveyer, and

Figure 5 is a fragmentary perspective view of a section of the present conveyer to clearly illustrate the peculiar formation of the wire strands and the manner in which they interlink with one another.

Referring to the drawing which shows a preferred embodiment, a wire conveyer is disclosed consisting of transverse wire strands 10a, 11a, 10b, 11b, etc., the strands 10 being of similar formation, while strands 11 are likewise of similar formation, although differing in certain characteristics but not in fundamental principle with strands 10. The wire strands 10a, 11a and 10b, 11b, etc., are pivotally connected at each end by means of closed loops 12 and 13 formed at the terminals of the strands 10 and 11, respectively. Intermediate the closed loop portions at the ends of each strand are straight portions connected by open loops, the strand 10 having portions 14 and 15 alternating and being connected by loops designated in their entirety by 16, 17, etc., Figure 1, the straight portions of one strand engaging with the open loops of adjacent interlinking strands as will be more fully explained. Strand 11, considered from either end, is formed first with a loop 18 connecting with a straight portion 15 of a length substantially equal to the portion 16 similarly identified in strand 10. Open loop 19 joins with portion 14 of slightly greater length.

The present conveyer is formed of sections which can be readily interlinked with or detached from other sections so as to vary the length of the conveyer to suit conditions. In Figure 2 a section is shown as including an upper strand 10 and a lower strand 11 pivotally connected at their ends by means of the closed loops 12 and 13 as described. More particularly considering the strand 10, it will be seen that the straight portion 14 is connected to closed loop 12 by a compound right angled bend 21, Figure 5, providing a seat for engagement with the loop formed on the strand of the adjacent section. The other end 14 also terminates in a compound right angled bend 21 which continues downwardly providing the leg portion 22. Leg 22 is connected to leg 23 by the rounded cusp 24 to complete the open loop identified in its entirety by 16, Figure 1. Continuing from the open loop is a straight portion 15 connected with leg 23 by a single right angled bend 25, a bend of similar character being duplicated at the other end of 15. The second open loop 17 formed in strand 120

10, considered from either end of the strand, is substantially the same as the loop described having downwardly extending leg portions, being connected by the rounded cusp, in this instance 5 identified by 26. Connecting with this second loop is a straight portion 14 which forms with the leg of the same a compound right angled bend similar to 21. Mention is again made of the fact that the portions 14 are of slightly 10 greater length than portions 15 which alternate with the former throughout the length of the strand, locating the open loops at definite intervals.

The lower strand 11, considered from either 15 end, is formed with an open loop 18, Figure 1, having leg portions connected by a cusp 27 and a second loop 19 also consisting of leg portions connected by a cusp 28, the loops being joined by 15 connecting with the inner legs by a single 20 right angled bend 30. Continuing from the second loop 19 it will be seen, Figure 5, that the straight portion 14 connects therewith by a compound right angled bend 31, providing a seat 25 for engagement with the cusp 24 of strand 10. Portion 14 is of greater length than 15 on strand 10 located directly above and terminates in a bend identical with 31. The next open loop 30 formed in this strand is similar in all respects having cusp 27 as described with reference to loop 18. Any further description of the formation of the various strands would be a repetition of that already given so attention will be directed to their peculiar curvature which permits interlinking of the strands.

35 In Figure 5 the two strands above described, forming a section of the present conveyer, are shown in perspective in order to more clearly illustrate the angularity of the various open loops formed in the strands. Strand 10 first provides 40 a seat 21 for engagement with a co-operating loop and to the other end of the straight portion 14 provides another seat 21 and an open loop, the cusp 24 of which is bent at an angle to a plane passing through the various straight portions 14 and 15 of the strands. The second loop 45 17 formed in strand 10 connects with loop 16 by portion 15 and has its cusp 26 bent so as to lie in a plane at an angle to that passing through the straight portions and which is also in opposition to the angularity of the first loop so that 50 these loops in effect face each other. The remainder of the strand is of similar formation having portions 14 providing seats as described, alternating with pairs of loops angularly bent so as to face each other. Strand 11 is formed so 55 as to locate a pair of loops, namely, 18 and 19, substantially within the portion 14 of strand 10. The loops are angularly bent with cusp 27 lying in a plane to accommodate a seat 21 of the strand 10 to be interlinked therewith, Figure 1. In like manner cusp 28 is bent to engage a seat 60 21 of the strand locating portion 14 on the upper side of the inner legs of the loop. The same constructional feature is repeated as will be apparent from Figure 5, which clearly illustrates the manner in which cusps 24 and 26 of strand 65 10 having the angular portions described engage the seats formed on 14 of strand 11. The portion 14 is likewise located over the inner legs of the loop.

70 It will be appreciated from the foregoing that the present conveyer consists of sections of two strands pivotally linked at their ends and each having special formation which permits the strands to be interlinked with each other and

the sections with adjacent sections in a like manner. In Figure 4 is shown the method of linking the sections together. Beginning with either end the sections are interlinked by inserting successively the straight portion 15 and the inner legs of the loops connecting therewith within and under the wider straight portions 14 of the adjacent strand. This brings the seats 21 on portion 14 over the inner legs of the loops having cusps 27 and 28 which when the strands are 80 finally interlinked have engagement therewith.

85 A feature of the invention which results from the above form of interlock is the flexibility of the conveyer enabling it to bend in one direction approximately ninety degrees. This is desirable as it enables a conveyer of the present construction to pass over sharp edges so that one endless belt may be associated with another in a manner to continue the movements of the articles conveyed thereby without difficulty. As illustrated in Figure 2 various strands will have movement on their adjacent strand 90 downwardly away from the plane of the drawing. This can easily be explained since in every instance the straight portions 14 are located over the inner legs with the compound right angled bends 21 and 31 passing through the various loops. No interference is presented to pivotal movement of the strand on its adjacent strand when the same is rotated downwardly away 95 from the plane of the drawing, but reverse movement upwardly from a flat position is prevented by engagement of the legs of the loops with the rounded cusp portions of the supporting loops.

100 Figure 3 represents a sectional view of the 110 conveyer and illustrates clearly the substantially flat upper surface of the same which is formed to a great extent by the straight portions 14 and 15 of the various strands, which portions lie in the same plane. The curvature given the loops and the bends therein including the seats 21 and 31 are designed so as to be located on the undersurface forming depressions only on the upper surface whereby the upper surface is formed substantially by the straight portions.

115 It is to be understood that I do not wish to be limited by the exact embodiment of the device shown, which is merely by way of illustration and not limitation, as various and other forms of the device will of course be apparent 120 to those skilled in the art without departing from the spirit of the invention or the scope of the claims.

I claim:

1. A flexible conveyer composed of a plurality of relatively separable interlinking sections each of which comprises a pair of transverse strands connected at their ends, each of said strands having alternate straight portions and looped portions, the looped portions connecting with the straight portions of adjacent strands to interlink the strands.

2. A flexible conveyer composed of a plurality of sections each of which comprises a pair of transverse strands, means formed on the ends of the strands for pivotally connecting two strands to form a section, said strands having a formation permitting one to interlink with the other and a section to interlink with adjacent sections, said sections being separable from adjacent interlinked sections.

3. A conveyer of the class described, in combination, a plurality of interlinked sections, each section including a formed strand interlinking with and being connected at its ends to

- another strand of dissimilar formation, said sections being held to one another by the interlinking of the strands only, said interlinking being of a character whereby the sections may be 5 separated by manual manipulation. 80
4. A conveyer of the class described, in combination, a plurality of interlinked sections, each section including a transverse strand of wire providing a plurality of open loops connected at its ends to another strand of wire of substantially similar shape, said loops of one strand engaging seats formed on connected strands whereby the strands are interlinked and the sections are interlinked. 85
- 15 5. A conveyer of the class described, in combination, a plurality of interlinked sections, each section including a pair of strands, closed loops formed on the ends of the strands for pivotally connecting the pair together, and open loops 90 formed in each strand for interlinking with its connected strand and a strand of the adjacent section respectively. 95
- 20 6. A flexible wire conveyer composed of a plurality of interlinking sections each of which 100 comprises a pair of wire strands, closed loops formed on the ends of the strands for connecting them together in pairs, each strand having alternate straight portions and open loops, whereby the loops have engagement with the 105 straight portions of adjacent strands to interlink the strands. 110
7. A flexible wire conveyer composed of a plurality of interlinking sections each of which 115 comprises a pair of wire strands, closed loops formed on the ends of the strands for connecting them together in pairs, each strand having alternate straight portions and open loops, seats provided on certain straight portions for engaging with the loops of an adjacent strand to 120 interlink the strands. 125
- 25 8. A flexible wire conveyer composed of a plurality of interlinking sections each of which 130 comprises a pair of wire strands, closed loops formed on the ends of the strands for connecting them together in pairs, each strand having alternate straight portions and open loops, seats provided on certain straight portions for engaging with the loops of an adjacent strand to 135 interlink the strands, said loops being bent at an angle to a plane passing through the portions, whereby the strands have pivoted movement in one direction on their interlinked strands. 140
- 30 9. A flexible wire conveyer composed of a plurality of interlinking sections each of which 145 comprises a pair of wire strands, closed loops formed on the ends of the strands for connecting them together in pairs, each strand having alternate straight portions and open loops, seats provided on certain straight portions for engaging with the loops of an adjacent strand to 150 interlink the strands, said loops being bent at an angle to a plane passing through the portions, the plane of adjacent loops of any strand being non-parallel, whereby the strands may interlink and pivotal movement between interlinked strands is possible in only one direction. 155
- 35 10. A flexible wire conveyer composed of a plurality of interlinking sections each of which 160 comprises a pair of wire strands, closed loops formed on the ends of the strands for connecting them together in pairs, each strand having alternate straight portions and open loops, seats provided on certain straight portions for engaging with the loops of an adjacent strand to 165 interlink the strands. 170
- 40 11. A flexible wire conveyer composed of a plurality of interlinking sections each of which 175 comprises a pair of wire strands, closed loops formed on the ends of the strands for connecting them together in pairs, each strand having straight portions separated by open loops, adjacent straight portions being of different lengths and alternate straight portions being of the same 180 length, and said strands interlinking by the loops of one strand engaging seats formed on a straight portion of the interlinked strand. 185
- 45 12. A wire conveyer belt composed of a plurality of interlinked sections, each section including a formed strand interlinking with and being connected at its ends to another strand of dissimilar formation, said sections being joined by interlinking of adjacent strands of dissimilar character, whereby said sections are held in connected 190 relation for all practical purposes but are detachable through manual manipulation of the connected strands to permit lengthening or shortening of the conveyer. 195
- 50 13. A flexible wire fabric composed of a plurality of wire strands, each strand having alternating straight portions and loops, and each strand interlinking with adjacent strands by the straight portions engaging with loops of one adjacent strand and by the loops engaging with the 200 straight portions of the other adjacent strands. 205
- 55 14. A flexible wire fabric composed of a plurality of transverse wire strands, certain of the strands being pivotally connected at their ends, each strand being formed with spaced loops of 210 substantially U-shape and each strand interlinking with adjacent strands by a portion of the adjacent strand passing through each loop thereof. 215
- 60 15. A flexible wire fabric composed of a plurality of transverse wire strands, certain of the strands being pivotally connected at their ends, and each strand interlinking with adjacent strands at points intermediate their ends, certain 220 interlinked strands being separable and said interlinking portions and pivotally connected ends producing a fabric having a maximum thickness substantially twice that of the wire of which the strands are formed. 225
- 65 16. A flexible wire fabric composed of a plurality of transverse wire strands, certain of the strands being pivotally connected at their ends, and each strand interlinking with adjacent strands at points intermediate their ends, certain 230 interlinked strands being separable, and said fabric being characterized by the ability of the interlinked strands to pivot to one another substantially ninety degrees in one direction and to resist similar movement in the other direction. 235
- 70 17. A flexible wire fabric composed of a plurality of transverse wire strands, certain of the strands being pivotally connected at their ends, and each strand interlinking with adjacent strands at points intermediate their ends, certain 240 interlinked strands being separable, and said fabric being characterized by the dissimilarity of its surfaces, one surface being substantially flat and the opposite surface having a pronounced wavy contour. 245
